DESK CALENDAR

Howard L. Moore, Cochranton, Pa.
Filed July 13, 1960, Ser. No. 61,350

Term of patent 14 years
(Cl. D74—5)

FIG. 1.

FIG. 2.

Fig. 1.Fig. 2.

Fig. 1 is a top plan view of a desk calendar showing my new design;

Fig. 2 is a right side elevational view thereof as it appears in flattened position;

Fig. 3 is a bottom plan view of the desk calendar shown in Fig. 1; and

Fig. 4 is a right side elevational view thereof.

The essential features of my design reside in the portions shown in solid lines on the drawings.

I claim:

The ornamental design for a desk calendar, as shown and described.
